UNITED STATES PATENT OFFICE.

GEORGE R. RICHARDSON, OF LEON, WISCONSIN.

TRACE-END SUPPORT.

SPECIFICATION forming part of Letters Patent No. 687,652, dated November 26, 1901.

Application filed November 10, 1900. Serial No. 38,112. (No model.)

To all whom it may concern:

Be it known that I, GEORGE R. RICHARDSON, a citizen of the United States, residing at Leon, in the county of Monroe and State 5 of Wisconsin, have invented certain new and useful Improvements in Trace-Carriers; and I do hereby declare the following to be a full, clear, and exact description of the invention, such as will enable others skilled in the art to 10 to which it appertains to make and use the same.

This invention provides a trace-carrier that can be manipulated by one hand during the operation of attaching and removing the traces therefrom and which will preclude the 15 casual displacement of the said traces when coupled thereto.

For a full description of the invention and the merits thereof and also to acquire a 20 knowledge of the details of construction of the means for effecting the result reference is to be had to the following description and drawings hereto attached.

While the essential and characteristic features of the invention are necessarily susceptible of modification, still the preferred embodiment of the invention is illustrated in the accompanying drawings, in which—

Figure 1 is a perspective view of a trace-carrier embodying the invention. Fig. 2 is a 30 top plan view. Fig. 3 is a transverse section. Fig. 4 is a side elevation.

Corresponding and like parts are referred to in the following description and indicated in all the views of the drawings by the same 35 reference characters.

The trace-carrier comprises a bar 1, oppositely-disposed hooks 2 and 3, and a spring tongue or mousing 4. The bar 1 is common to the hooks 2 and 3 and constitutes a shank 40 therefor, and said hooks spring from the terminals thereof. The extremities of the hooks 2 and 3 are widened in the plane of the hooks to form heads 5, which project into the space inclosed by said hooks and are adapted to 45 prevent displacement of the traces when coupled thereto. Lateral extensions 6 project from opposite sides of the bar 1 at a point opposite the space formed between the terminals of the hooks 2 and 3 and are adapted to 50 receive the fastenings by means of which the device is secured to the harness or other part. Moreover, these lateral extensions 6 hold the

hooks 2 and 3 in an upright position and prevent their lateral tilting when the device is subjected to sidewise strain.

The spring tongue or mousing 4 is attached at one end to the outer terminal of a lateral extension 6, and its opposite end terminates about central of the space formed between the extremities of the hooks 2 and 3, so as to 60 obstruct the passage therethrough of the traces or other part to be attached to the carrier and prevent accidental disengagement therefrom. The spring tongue or mousing 4 inclines inwardly and upwardly, and its outer 65 lower end is fitted to a seat 7, formed with or applied to the extension 6, having the part 4 attached thereto. The seat 7 is preferably integral with the lateral extension 6, and its upper face inclines in conformity to the inclination of the spring-tongue 4. A screw or kindred fastening 8 is employed for attaching the part 4 to the seat and lateral extension 6. The part 4 tapers in width from its outer to its inner end, the latter terminating 75 medially of the heads 5 and adapted to be sprung either outward or inward, according as the trace is to be removed or attached to the carrier. The passage between the heads 5 is normally obstructed by the tongue or mousing 4, and the latter being constructed so as to move either inward or outward enables the trace to be coupled or uncoupled by a single hand, the tongue moving in the direction of pressure applied thereto. The opposing faces 80 of the heads 5 flare in opposite directions from a central point to facilitate and guide the trace in its movement through the said passage either inward or outward. The free end of the tongue 4 normally stands in line with 85 the contracted central portion of the passage between the said heads 5.

By having a spring tongue or mousing 4 located in a plane about at a right angle to the plane of the body of the trace-carrier it is not 90 in the way of the traces or other part attached to the device and in nowise interferes with a ready coupling and uncoupling of the traces. In practice the trace to be attached to the carrier is passed between the heads or 95 terminals of the hooks 2 and 3 and depresses the free end of the spring-tongue 4, and after the eye of the trace has cleared the heads 5 a movement either to the right or to the left

will cause the trace to clear the spring-tongue and to engage with one or the other of the hooks 2 and 3, and the tongue being released will spring outward into normal position and close the passage between the terminals of the hooks and prevent accidental disengagement of the trace. When it is required to remove the trace, it is brought opposite the passage formed between the extremities of the hooks 2 and 3 and moved outward and coming in contact with the free end of the tongue 4 presses the latter outward, thereby permitting the disengagement of the trace, and, when clear of the hooks and the spring-tongue, the latter will assume its normal position, as most clearly set forth.

Having thus described the invention, what is claimed as new is—

1. In a trace-carrier, oppositely-disposed hooks longitudinally alined and having their extremities spaced apart, a laterally-extending spring tongue or mousing supported at its outer end and having its inner end terminating in the space formed between the ex-

tremities of the said hooks to obstruct the 25 passage therebetween and adapted to move either inward or outward with the part applied to or removed from said carrier, substantially as set forth.

2. In a trace-carrier, a base, oppositely-disposed hooks longitudinally alined and having their extremities spaced apart, a seat to one side of the plane of the hooks and in transverse alinement with the space formed between their extremities, and a spring-tongue 35 secured at its outer end to the said seat and having its inner end terminating in the space formed between the extremities of the hooks and adapted to move freely either inward or outward when applying the part to or removing it from the carrier, substantially as set forth.

In testimony whereof I affix my signature in presence of two witnesses.

GEORGE R. RICHARDSON.
